United States Patent Office.

LEMAN B. PITCHER, OF SALINA, NEW YORK.

Letters Patent No. 80,212, dated July 21, 1868.

IMPROVEMENT IN SHAFTING.

The Schedule referred to in these Letters Patent and making part of the same.

TO ALL WHOM IT MAY CONCERN:

Be it known that I, LEMAN B. PITCHER, of the town of Salina, in the county of Onondaga, and State of New York, have invented certain new and useful Improvements in Shafting; and I do hereby declare that the following is a full, clear, and exact description of the same, reference being had to the annexed drawing, which forms a part of this specification, and represents in perspective the improvements which I claim.

Said improvements consist of a non-revolving bent shaft, either solid or hollow, and are intended to apply more particularly to the shafting for hollow revolving cylinders, used for manufacturing purposes, with an open feeding-hole in the head, and are intended to afford a strong support for the cylinder to revolve on, and so bent that the hole in said head shall be kept nearly free and open while feeding said cylinder.

F represents a frame, upon which a cylinder, C, is mounted, on the non-revolving shaft S, with bearings b b, in the ordinary form. I continue the non-revolving shaft S in the form of a strong bent arm, A, until it passes through the supporting-beam B, where that end is held by a nut, or any other ordinary device. It should be bent in such form and curve that it will just clear the rim of the open feeding-head, and afford the least possible obstruction to the same. Although not indispensable, I prefer to make the non-revolving shaft S and the strong arm A hollow, either for the purposes of lubrication or to introduce any fluid that may be desired in the cylinder C, for assisting or facilitating any manufacturing operation that may be carried on therein.

The size of the hole in the non-revolving shaft, and how far it shall extend into the arm A and the non-revolving shaft S, will vary according to the use that may be intended.

The dots o o are openings for lubricating the bearings b b, by passing the lubricating-material through the tube running through the non-revolving shaft, as aforesaid, when that is desired.

One or more faucets, d, may be used when it is desired to introduce the fluid into the cylinder C, as aforesaid.

To regulate the flow of such fluid, I use the regulator z, placed at a convenient point on the arm A, in the form of a cock, for that purpose.

M is a funnel, in any common form, for receiving the fluid.

What I claim as my invention, and desire to secure by Letters Patent, is—

The non-revolving bent shaft A and S, when made and applied for the purpose aforesaid, substantially in the manner above described.

LEMAN B. PITCHER.
